WORKING PLATFORM FOR ELEVATOR
HOISTWAYS

Russell George Tilton, Mountain Lakes, N. J., assignor to Otis Elevator Company, New York, N. Y., a corporation of New Jersey.

Application August 2, 1944, Serial No. 547,725

7 Claims. (Cl. 304—29)

The invention relates to apparatus for installing elevator hoistway equipment.

In elevator hoistways, in order that various equipment may be installed, it is necessary to work at various hoistway levels. The practice is to start by installing the sections of elevator car guide rails at the bottom of the hoistway and work up. Various arrangements are employed for supporting the workmen, the approved arrangement being to provide a temporary working platform guided on the elevator car guide rails as the rail sections are installed. The invention is especially directed to temporary hoistway working platforms of this character.

Owing to the different sizes of elevator hoistways and to the fact that elevator installations are made at widely separated points, it has been the practice to construct these platforms to fit the particular jobs. This is expensive and it is desirable that such expense be kept at a minimum. Also it is important that such working platforms be safe.

One feature of the invention resides in supporting framework for a working platform which is adjustable to accommodate different size hoistways.

Another feature of the invention resides in supporting framework for a working platform which automatically locks the platform against descent.

Other features and advantages of the invention will become apparent from the following description and appended claims.

In carrying out the invention according to the preferred arrangement, the supporting framework for the platform comprises a pair of levers pivotally joined at their centers to form an expandable X frame. The guide shoes for guiding the platform on the elevator car guide rails are carried by the X frame. These guide shoes are elongated and are secured to the ends of the levers of the X frame. The connections at one end of the frame are pivotal while the connections at the other end are slideable to enable the supporting framework to be adjusted to fit hoistways of different widths. The floors of the platforms are fabricated on the jobs or in the shop to fit the particular hoistways. Brace rods are carried by the X frame at the front and back. A safety device is carried by the framework which acts automatically to engage the rails and thus support the platform. To lower the platform this safety device is released. Block and tackle may be provided for raising and lowering the platform and a canopy may be provided to protect the

workmen against objects falling in the hoistway.

In the drawings:

Figure 1 is a front view of a temporary working platform embodying the invention, mounted on the lowermost guide rail sections;

Figure 2 is a view in section taken along the line 2—2 of Figure 1;

Figure 3 is a view of the elevator hoistway illustrating mechanism for manipulating the platform;

Figure 4 is a detail with parts omitted illustrating one of the safety brakes applied to a guide rail, as viewed toward one side of the rail;

Figure 5 is a view in section taken along the line 5—5 of Figure 4; and

Figure 6 is a front view of the supporting framework illustrating a step in mounting the framework on the guide rails.

Referring first to Figures 1 and 2, the supporting framework for the working platform comprises an expandable X frame formed of a pair of levers 10 and 11 pivotally mounted at the middle on a king pin 12. Each lever comprises a pair of boards 13 and 14, those for lever 10 being inside those for lever 11. Each lever has a pair of metal plates 15 at its center on opposite sides thereof, those for lever 10 being on the inside of the frame and those for lever 11 being on the outside of the frame. These plates serve as bearing supports for the king pin. Secured to the ends of the levers are a pair of elongated wooden stiles 16 and 17, one on each side of the frame. These stiles have elongated grooves 18 (see Figure 5) in their outer faces which fit rather loosely over the guide rails 20 and 21 for the elevator car and act as guide shoes to guide the working platform in its movement in the hoistway. Each guide shoe is provided at its lower end with a pair of metal plates 22, one on each side thereof, secured thereto as by bolts. Each of the boards 13 and 14 of each lever 10 and 11 has secured to the lower end thereof a metal plate 23. The lower ends of the levers are pivotally secured to the lower ends of the guide shoes by pivot bolts 24 extending through the plates 22 and 23. Each guide shoe is also provided at its upper end with a pair of metal plates 25, one on each side thereof, secured thereto as by bolts. Each of boards 13 and 14 of each lever 10 and 11 has secured to the upper end thereof a metal plate 26. The upper ends of the levers are slidably secured to the guide shoes by bolts 27 carried by plates 26 and extending through aligned elongated slots 28 in plates 25. The X frame is locked in expanded position with respect to the guide shoes. This is effected for

each side of the frame by a threaded rod 30 pivotally supported by bolt 27 and carrying adjustable clamping nuts 31. These nuts seat in an aperture formed in a metal angle member 32 and having a side opening to admit the rod. This angle member is secured to a metal channel member 33 in turn secured to the back of the guide shoe as by the bolts securing plates 25 to the shoe.

The floor is of wood and is illustrated as comprising a pair of joists 35 joined by stringers 36 and 37. A working surface 38 which may be made of plywood is mounted on the stringers 37. The joists rest on the top of plates 25. Another metal channel member 40 is secured to the back of each guide shoe as by the bolts securing plates 25 to the shoe. The upper ends of these channels extend above the guide shoes. The floor is secured to the guide shoes as by bolts 41 extending through the upper ends of the channels and the joists 35.

The front and back of the floor are braced by means of main braces 45 extending from the corners of the floor to the lower ends of the guide shoes. These braces are in the form of metal pipes with their ends flattened and drilled to form eyelets. Each of plates 22 has a flange 46 extending outwardly therefrom at right angles. The lower ends of the main braces are secured to these flanges as by bolts 47 extending through the lower end eyelets. The upper ends of the braces are secured to joists 35 as by bolts 48 extending through the upper end eyelets. Additional bracing is provided by secondary braces or tie rods 50. These braces also are in the form of metal pipes with their ends flattened and drilled to form eyelets. The secondary braces are secured at their lower ends to the lower ends of the main braces as by bolts 51 extending through the lower end eyelets of the secondary braces. Sleeves 52 are slidably mounted on the main braces and at their upper ends the secondary braces are secured to these sleeves as by set screws 53 extending through the upper end eyelets of the secondary braces and threaded apertures in the sleeves to engage the main braces. The secondary braces are held together at the point of crossing as by U clamps 54.

The platform is automatically locked against descent by means of safety brakes, one for each guide rail. Various forms of safety brakes may be employed, one which has been found satisfactory being illustrated in Figures 4 and 5. This brake comprises a brake block 60 secured as by screws 59 between and to plates 22 at the lower ends thereof. The block has a straight sided face 61 for engaging one side of the guide rail and a bevel portion 62 facing but spaced from the other side of the guide rail. A roller 63 is positioned between the bevel portion 62 and the guide rail and is rotatably mounted on a pin 64 carried by a supporting plate 65. This plate is bent at right angles at its upper end and has a spindle 66 secured thereto and extending upwardly therefrom. The spindle extends through an aperture 67 in the horizontal arm of an angle 68 secured as by a bolt 70 to the right hand one of the plates 22 as viewed in Figure 5. Arranged between a head 71 secured to the top of the spindle and the angle is a compression spring 72. This spring pushing upwardly against head 71 acts through the spindle and supporting plate to bias the roller into position wedged between bevel portion 62 of the safety block and the guide rail. Thus both brake shoes are normally applied to the guide rail to lock the platform against descent.

Each safety brake is released by pushing downwardly on supporting plate 65. This is effected by means of a bell crank lever 75, one arm 76 of which engages a spool 77 on the end of a spindle 78 secured to supporting plate 65. Rotation of the bell crank in a direction to push downwardly on the spool, moves plates 65 downwardly and thus releases the roller from the guide rail. The supporting plate has a tapered tail 69 which extends through a slot in a plate 79 secured to the bottom of the safety block and acts to force the roller away from the rail when the plate is pushed downwardly by the bell crank. The bell crank is pivotally mounted on a pivot bolt 80 mounted on the right hand plate 22 of Figure 5. The other arm 81 of the bell crank is provided with an aperture in its outer end to which an operating chain 82 is secured.

Referring to Figure 1, operating chain 82 is illustrated as a one-piece chain extending from the operating arm of the bell crank of the safety brake on one side of the frame to the operating arm of the bell crank of the safety brake on the other side of the frame. This chain is led through pipes 83 carried by the lower arms of the X frame and terminating near the pivot point of the frame. The middle portion of the chain above the pipes 83 runs over the pulley wheel of a pulley block 84. The pulley block is connected to an operating ring 85 above the floor by a chain 86 which extends through an aperture 87 in the floor.

Referring to Figure 3, the platform is raised and lowered by means of block and tackle 88. The upper pulley block 90 of this mechanism is secured as by a rope 91 to a cross beam 92 at the top of the hoistway. The lower pulley block 93 is secured as by a rope 94 and hook 95 to the king pin 12, the rope 94 extending through an aperture 96 in the floor. An anchor 97 is connected by a chain 98 to the king pin 12, the chain passing through an aperture 100 in the floor. A canopy 101 which may be in the form of a frame covered by wire netting may be provided for the platform to protect the workmen against falling objects. This canopy is supported by pipe standards 102 mounted in pipe flanges 103, one at each corner of the floor. An opening is provided in the canopy for the tackle.

The supporting framework is adapted to be used over and over again and on hoistways of different sizes. It may be kept as one assembled piece of mechanism in a collapsed state in which event U clamps 54 are removed and the upper ends of the secondary braces are disconnected from sleeves 52 to enable the supporting framework to be folded in a compact unit; or it may be kept in three separate sub-assemblies comprising as one sub-assembly the folded X frame and as the other two sub-assemblies the two guide shoes with the brace rods attached thereto and folded against the shoes.

In installing the working platform, the lowermost sections of the guide rails 20 and 21 are first installed. These rails are fastened by clips 105 to rail brackets 106 secured to the hoistway walls or structure, these clips and brackets not being shown in Figure 2. As an aid to understanding the installing of the supporting framework reference may be had to Figure 6 in which for convenience various parts of the mechanism are not shown. Supporting blocks 107 for the framework are placed on the floor 108 of the hoistway adjacent the rails and levelled to place their upper ends in horizontal alignment. The

supporting framework in slightly expanded condition and with the threaded rods 30 released as illustrated in Figure 6, is placed in position with one of the guide shoes on the guide rail with the safety block beneath that guide shoe resting on the top of block 107. In mounting the guide shoe the safety brake is temporarily released by rotating the operating bell crank to enable the guide rail to enter the safety block between face 61 and roller 63. The guide shoe is then secured to the rail as by lashing it with ropes and the X frame expanded to position the other guide shoe on the other guide rail. The safety block of the other safety brake is placed on the other block 107, the safety brake being temporarily released in effecting this mounting. The threaded rods 30 are now inserted in the apertures in angles 32 with the lower nuts beneath the angles and the nuts adjusted to provide about $\frac{1}{8}$ " operating clearance between the guide shoes and rails whereupon the nuts are tightened to lock the X frame in expanded position.

Referring now to Figures 1 and 2, the floor is fabricated to fit the hoistway and a canopy if provided is constructed and mounted thereon. The floor is secured to the channel members 40 at the upper ends of the guide shoes. The braces which up to this time have been tied to the guide shoes are now released. Holes are drilled at the corners of the platform through joists 35 and the upper ends of the main braces are secured to the platform by bolts 48. Several apertures are provided in flanges 46 (see Figure 2) for adjusting the lower ends of the main braces to adjust for hoistways of considerable variation in distance from front to back. The upper ends of the secondary braces are then secured to the main braces and these secondary braces are secured together at their points of crossing by U clamps 54. The chain 86 is now inserted through the aperture 87 formed in the floor of the platform and hooked onto pulley block 84 for the safety operating chain. Referring to Figure 3 upper pulley block 90 of the hoisting block and tackle is secured to the crossbeam at the upper end of the hoistway. Rope 94 is inserted through aperture 96 and hooked onto king pin 12, thus connecting lower pulley block 93 to the king pin. Anchor chain 98 is inserted through aperture 100 and secured at its lower end to the king pin. The fall rope of the tackle is then pulled downwardly to lift the platform sufficiently for the blocks 107 to be removed and the fall rope is snubbed around the anchor. The platform is held by the safety brakes with the snubbing of the fall rope on the anchor as an added factor of safety.

It is preferable especially in case of long rail sections, to mount the lowermost rail sections on the two lower brackets and to use the working platform for mounting next brackets and securing the top of the rail sections thereto. To raise the platform, the fall rope of the block and tackle is pulled downwardly until the platform is raised to the desired position and the rope is then re-snubbed on anchor 97. The safety brakes release automatically when the platform is raised. The platform is moved upwardly for mounting each succeeding pair of rail brackets and, in instances where the distance between rail brackets is considerable, to enable the next brackets to be installed the platform may be moved into position above the top of the last installed rail sections a distance equal to as much as one half the height

of the guide shoes. Succeeding rail sections are joined by fish plates 110 as these sections are installed. To lower the platform, the safety brackets are released by pulling up on ring 85 and the hoisting tackle is let out until the platform reaches the desired position, whereupon the ring is released to apply the safety brakes and the fall rope is snubbed onto the anchor.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. Supporting framework for a temporary working platform adapted to run on a pair of guide rails in an elevator hoistway comprising; a pair of elongated guide shoes, one for each guide rail; an expandible frame connecting said guide shoes to enable the framework to be adjusted to fit hoistways of different widths; and means for locking the framework in adjusted position.

2. Supporting framework for a temporary working platform adapted to run on a pair of guide rails in an elevator hoistway comprising; a pair of guide shoes, one for each guide rail; means connecting said guide shoes; a safety brake carried by each guide shoe and normally engaging the guide rail to prevent descent of the platform; and means for releasing said safety brakes to enable the platform to be lowered.

3. A temporary working platform for operation on a pair of guide rails disposed on opposite sides of an elevator hoistway, said platform having a floor and supporting frame-work therefor comprising; a pair of elongated guide shoes, one for each guide rail; an expandible X frame connecting said guide shoes to enable the framework to span guide rails for hoistways of different widths; means for locking the framework in position spanning the rails; and a safety brake carried by each guide shoe biased to normally engage the guide rail.

4. A temporary working platform for operation on a pair of guide rails oppositely disposed on each side of an elevator hoistway, said platform having a floor and supporting framework therefor comprising; a pair of elongated guide shoes, one for each guide rail; an expandible X frame connecting said guide shoes to enable the framework to span guide rails for hoistways of different widths; means for locking said X frame in expanded condition with respect to said guide shoes to lock the framework in position spanning the rails; means for securing the floor to the upper ends of said guide shoes; braces connecting the lower ends of said guide shoes to the corners of said floor; a safety brake for each guide shoe carried by the lower end thereof and biased normally to engage the guide rail; and means for manually releasing said safety brakes.

5. An elevator hoistway temporary working platform having a floor and supporting frame-work therefor comprising; a king pin; a pair of crossed levers pivotally mounted at their centers on said king pin for relative movement to form an expandible X frame; a pair of elongated guide shoes, one for each elevator car guide rail; means pivotally securing one end of one of said levers to one end of one of said guide shoes and pivotally securing the corresponding end of the other of

said levers to the corresponding end of the other of said guide shoes; means slidably connecting the other end of said one lever to the other end of said other guide shoe and slidably connecting the other end of said other lever to the other end of said one guide shoe, thereby enabling the framework to span guide rails for hoistways of different widths; and means for locking the framework in position spanning the rails.

6. An elevator hoistway temporary working platform having a floor and supporting framework therefor comprising; a king pin; a pair of crossed levers pivotally mounted at their centers on said king pin for relative movement to form an expandible X frame; a pair of elongated guide shoes, one for each elevator car guide rail; means pivotally securing the lower end of one of said levers to the lower end of one of said guide shoes and pivotally securing the lower end of the other of said levers to the lower end of the other of said guide shoes; means slidably connecting the upper end of said one lever to the upper end of said other guide shoe and slidably connecting the upper end of said other lever to the upper end of said one guide shoe, thereby enabling the framework to span guide rails for hoistways of different widths; means for locking the upper ends of said levers to the upper ends of their respective guide shoes to lock the framework in position spanning the rails; means for securing the floor to the upper ends of said guide shoes; and braces connecting the lower ends of said guide shoes to the corners of said floor.

7. An elevator hoistway temporary working platform having a floor and supporting framework therefor comprising; a king pin; a pair of crossed levers pivotally mounted at their centers on said king pin for relative movement to form an expandible X frame; a pair of elongated guide shoes, one for each elevator car guide rail; means pivotally securing the lower end of one of said levers to the lower end of one of said guide shoes and pivotally securing the lower end of the other of said levers to the lower end of the other of said guide shoes; means slidably connecting the upper end of said one lever to the upper end of said other guide shoe and slidably connecting the upper end of said other lever to the upper end of said one guide shoe, thereby enabling the framework to span guide rails for hoistways of different widths; means for locking the upper ends of said levers to the upper ends of their respective guide shoes to lock the framework in position spanning the rails; means for securing the floor to the upper ends of said guide shoes; braces connecting the lower ends of said guide shoes to the corner of said floor; tie rods cross connecting said braces; a safety brake for each guide shoe carried by the lower end thereof to engage the guide rail, each brake comprising resilient means normally applying the brake to the rail to hold said platform against descent; and means for manually releasing said safety brakes to enable the platform to be lowered.

RUSSELL GEORGE TILTON.
